US00D918848S

(12) **United States Design Patent** (10) Patent No.: **US D918,848 S**
(45) Date of Patent: **** May 11, 2021**

(54) **RETAINER OF CEILING HEATER FOR SEMICONDUCTOR FABRICATION APPARATUS**

(71) Applicant: **KOKUSAI ELECTRIC CORPORATION**, Tokyo (JP)

(72) Inventors: **Shinobu Sugiura**, Toyama (JP); **Tetsuya Kosugi**, Toyama (JP); **Takatomo Yamaguchi**, Toyama (JP)

(73) Assignee: **KOKUSAI ELECTRIC CORPORATION**, Tokyo (JP)

(**) Term: **15 Years**

(21) Appl. No.: **29/718,687**

(22) Filed: **Dec. 27, 2019**

(30) **Foreign Application Priority Data**

Jul. 18, 2019 (JP) 2019-016134

(51) LOC (13) Cl. **13-03**

(52) U.S. Cl.

USPC **D13/182; D15/144.1**

(57) **CLAIM**

The ornamental design for a retainer of ceiling heater for semiconductor fabrication apparatus, as shown and described.

DESCRIPTION

FIG. 1 is a front, top and right side perspective view of a retainer of ceiling heater for semiconductor fabrication apparatus showing our new design; FIG. 2 is a front elevational view thereof; FIG. 3 is a left side elevational view thereof; FIG. 4 is a right side elevational view thereof; FIG. 5 is a top plan view thereof; and FIG. 6 is a bottom plan view thereof; and, FIG. 7 is a rear elevational view.

1 Claim, 4 Drawing Sheets
